CRUDE OIL TREATING APPARATUS

Glenn E. Mawhirter, Pawnee Rock, Kans.

Application November 18, 1943, Serial No. 510,829

8 Claims. (Cl. 252—362)

This invention relates to a crude oil treating apparatus, and has for the primary object the provision of a device of this character whereby batches of oil received from a continuous source of supply may be heated and chemically treated and at the same time agitated so that when reaching a settling tank, the water and other foreign matter which may be in the oil will more readily separate from the oil.

Another object of the invention is the provision of a device of the above stated character which will automatically arrange the oil as continuously received from the source into batches and permit a batch that has been formed to be chemically treated and at the same time agitated and to automatically deliver the treated batch to a settling tank when said device substantially completes the next batch.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation illustrating an oil treating apparatus constructed in accordance with my invention.

Figure 2 is a vertical sectional view illustrating the device.

Figure 3 is a fragmentary view, partly in section, showing a ratchet arrangement between an operating rod and a lever forming a part of the present invention.

Referring in detail to the drawing, the numeral 5 indicates a base on which is arranged a vertically disposed tank 6 closed at its upper end by a dome shaped top wall 7. The tank is divided approximately in half by a partition 8 forming upper and lower chambers 9 and 10. A flue casing 11 extends into the tank adjacent the base and has connected thereto and arranged vertically and exteriorly of the tank a flue pipe 12. A heater 13 is arranged in the flue casing for the purpose of heating the contents of the lower chamber 10. A crude oil supply pipe 14 connects with the lower chamber 10 adjacent the base and receives crude oil continuously while the device is in operation from a supply.

An oil transfer pipe 15 is carried by the partition 8 and connects the upper and lower chambers 9 and 10. The upper end of the pipe 15 is located slightly above the partition 8 while said

5 pipe extends a considerable distance downwardly in the chamber 10 and terminates in a goose neck 16, the end of which forms a valve seat for a valve element 17 including a stem 18 slideable in a guide 19.

A float shaft 20 is journaled in the chamber 10 adjacent the partition 8 and extends exteriorly of the tank and has secured thereto an arm 21. The arm is connected to the shaft 20 substantially intermediate the ends of said arm. A connecting rod 22 including a turn buckle 23 is connected to one end of the arm 21.

An arm 24 is secured to the float shaft 20 and is connected to the stem 18 of the valve 17 by a flexible element 25. A stem 26 of a float 27 is connected to the float shaft for imparting movement thereto by the rise and fall of the oil in the lower chamber 10.

The connecting rod 22 extends through a slot 28 formed in an arm 29. The arm 29 is secured substantially intermediate its ends to a shaft 30 equipped with an arm 31 within the upper chamber 9. The arm 31 is connected to a stem 32 by a flexible element 33. The stem forms a part of a valve 34 and is slidably supported by a guide 35. An outlet pipe 36 extends through a wall of the tank and is in communication with the upper chamber 9 being supported by the partition 8. The upper end of the outlet pipe 36 which connects with the upper chamber 9 is in the form of a valve seat to be engaged by the valve 34 to prevent the escape of oil from the upper chamber until such time that the valve element 34 is raised or elevated.

35 A pipe 38 is arranged in the upper chamber 9 adjacent the partition 8 and extends exteriorly of the tank to connect with a vertically arranged pipe 39 having communication with the lower chamber 10 adjacent the partition by a pipe 40. Arranged in the vertical pipe 39 is a pressure relief valve 41 of the conventional type, the purpose of which is to maintain a predetermined pressure in the lower tank before opening. The pipe 38 is provided with a series of jets or nozzles 42 extending in the direction of the partition 8, the purpose of which is to distribute pressure into the oil of the upper chamber for circulation upwardly therethrough and thereby bring about the agitation of the oil within the upper chamber.

40 A relief valve 45 connects with the upper chamber 9 and is carried by the top wall 7, the purpose of which is to permit pressure exceeding a predetermined amount to escape from the upper chamber 9 to the atmosphere.

45 A chemical supply pump (not shown) is con-

nected to the port 46 of the upper chamber 9 so that chemical may be introduced into the oil within the upper chamber 9 for chemically treating said oil.

The connecting rod 22 which extends through the slot 29 of the arm 29' has an arcuately curved dog 47 pivoted thereto and is spring influenced, as shown at 48. The dog 47 operates in the slot 29, as clearly shown in Figure 3, and the purpose of which is to establish a drive between the connecting rod and the arm 29' until sufficient resistance is offered to the movement of the arm 29' that will overcome the action of the spring 48 and permit the dog 47 to pivot sufficiently to permit the connecting rod 22 to slide relative to the arm 29'.

A stop 50 is arranged on the tank 6 for limiting the downward pivotal movement of one end of the arm 29'. The rod 22 may continue to move downwardly when the arm 29' engages with the stop 50 due to the arrangement of the dog 47 in the slot 29 and the spring 48.

The pressure relief valve 41 is adjusted so that a greater pressure may be maintained in the lower chamber 10 over the pressure maintained in the upper chamber 9. The heater 13 is fed with a fuel in any well known manner and as before stated, is for the purpose of heating the oil within the lower chamber 10.

In operation, when the float 27 is in its lowermost position the valves 17 and 34 are in seated position closing the pipe 15 and the outlet pipe 36. When the oil within the chamber 10 reaches a certain level the float 27 rises, imparting movement to the shaft 20 and through the connecting rod and its connection with the arm 29' the valve 34 is unseated. The unseating of the valve 34 will allow the escape of oil from the upper chamber 9 and as the chamber 9 substantially empties of oil a suction on the valve 34 by the oil passing out of the outlet pipe 36 causes the valve 34 to seat itself and thereby close the escape of oil from the chamber 9.

As the oil level within the chamber 10 continues to rise, a further movement of the float 27 will be made causing a further movement of the shaft 20 which unseats the valve 17. The pressure on the oil within the chamber 10 which exceeds any pressure that may be in the chamber 9 forces oil from the chamber 10 into the chamber 9 until the level of the oil in the chamber 10 falls to such an extent as to permit the valve 17 to close. Therefore, it will be seen that a batch of oil is accumulated in the chamber 9 while a batch of oil is accumulating within the chamber 10. Chemicals may be then introduced into the oil of the chamber 9 and as the pressure in the chamber 10 exceeds the pressure for which the relief valve 41 is set for, the excess pressure escapes through the jets 42 and passes upwardly through the chemically treated oil in the chamber 9 and thereby agitates said oil.

It is to be understood that the oil fed into the chamber 10 continuously is under pressure consequently building up a pressure within the chamber 10 and when said pressure exceeds the setting of the valve 41, the latter permits fluid in the upper portion of the chamber 10 to pass through the pipe 38 into the chamber 9. The oil rising in the chamber 10 also builds up pressure therein.

As before stated, when the batch of oil in the chamber 10 reaches a level therein sufficient to raise the float 27 the initial movement thereof unseats the valve 34 and permits the treated

batch of oil in the chamber 9 to escape. The valve 34 automatically seats itself when the batch of oil in the chamber 9 lowers beyond the valve 34 as to cause a suction thereon.

5 The outlet pipe 36 is preferably connected to a settling tank (not shown) so that the treated batches of oil received from the chamber 9 during the operation of the device may come to rest in the settling tank and being treated as before 10 described will bring about an easier separation of water and other foreign matter from the oil while in the settling tank.

15 While I have shown and described the preferred embodiment of my invention, it is to be understood that minor changes in construction combination and arrangement of parts may be made without departing from the spirit and scope of the invention as claimed.

Having thus described my invention, what I 20 claim is:

25 1. In an oil treating apparatus, a tank including upper and lower chambers and means for admitting a continuous flow of oil under pressure to said lower chamber, means for heating the oil in the lower chamber, means for intermittently admitting a predetermined volume of oil from the lower chamber to the upper chamber means for feeding a chemical into the upper chamber for chemical treatment of the oil therein, and means for discharging the treated oil from the upper chamber.

30 2. In an oil treating apparatus, a tank including upper and lower chambers and means for admitting a continuous flow of oil under pressure to said lower chamber, means for heating the oil in the lower chamber, means for intermittently admitting a predetermined volume of oil from the lower chamber to the upper chamber means for feeding a chemical into the upper 35 chamber for chemical treatment of the oil therein, means for discharging the treated oil from the upper chamber, and means for automatically admitting fluid under pressure to the upper chamber from the lower chamber when the pressure in the lower chamber exceeds a predetermined amount to bring about agitation of the oil in the upper chamber.

40 3. In an oil treating apparatus, a tank including upper and lower chambers and means for admitting a continuous flow of oil under pressure to said lower chamber, means for heating the oil in the lower chamber, means for intermittently admitting a predetermined volume of oil from the lower chamber to the upper chamber means for feeding a chemical into the upper chamber for chemical treatment of the oil therein, means for discharging the treated oil from the upper chamber, means for automatically admitting fluid under pressure to the upper chamber from the lower chamber when the pressure in the lower chamber exceeds a predetermined amount to bring about agitation of the oil in the upper chamber, and a pressure relief valve connected to the upper chamber for maintaining the pressure therein lower than the pressure within the lower chamber.

45 4. In an oil treating apparatus, a tank including upper and lower chambers and means for admitting a continuous flow of oil under pressure to said lower chamber, a heater for heating the oil in the lower chamber, a pipe connecting the upper and lower chambers, a float operated valve for controlling said pipe to periodically admit oil from the lower chamber into the upper chamber, means for feeding a chemical into the upper

chamber for mixing with the oil therein, a float operating in the lower chamber and including a float shaft connected to said float valve, an outlet pipe connected to the upper chamber, a gravity operated valve for controlling the outlet pipe, a second shaft connected to the gravity operated valve, and means connecting the second shaft to the float shaft.

5. In an oil treating apparatus, a tank including upper and lower chambers and means for admitting a continuous flow of oil under pressure to said lower chamber, a heater for heating the oil in the lower chamber, a pipe connecting the upper and lower chambers, a float operated valve for controlling said pipe to periodically admit oil from the lower chamber into the upper chamber, means for feeding a chemical into the upper chamber for mixing with the oil therein, a float operating in the lower chamber and including a float shaft connected to said float valve, an outlet pipe connected to the upper chamber, a gravity operated valve for controlling the outlet pipe, a second shaft connected to the gravity operated valve, arms secured to said shafts and one of said arms having a slot, a connecting rod connected to the other arm and extending through the slot, an arcuately curved dog pivoted on said connecting rod and operating in the slot and spring influenced, and a stop for limiting the pivotal movement of the slotted arm.

6. In an oil treating apparatus, a tank including upper and lower chambers and means for admitting a continuous flow of oil under pressure to said lower chamber, a heater for heating the oil in the lower chamber, a pipe connecting the upper and lower chambers, a float operated valve for controlling said pipe to periodically admit oil from the lower chamber into the upper chamber, means for feeding a chemical into the upper chamber for mixing with the oil therein, a float operating in the lower chamber and including a float shaft connected to said float valve, an outlet pipe connected to the upper chamber, a gravity operated valve for controlling the outlet pipe, a second shaft connected to the gravity operated valve, arms secured to said shafts and one of said arms having a slot, a connecting rod

connected to the other arm and extending through the slot, an arcuately curved dog pivoted on said connecting rod and operating in the slot and spring influenced, a stop for limiting the pivotal movement of the slotted arm, and a pressure transfer pipe connecting the upper and lower chambers and including a pressure relief valve for admitting fluid under pressure through said pressure transfer pipe to the upper chamber from the lower chamber when the pressure in the lower chamber exceeds the pressure in the upper chamber.

7. In an oil treating apparatus, a tank including upper and lower chambers and means for admitting a continuous flow of oil under pressure to said lower chamber means for admitting a chemical to said upper chamber, a heater for heating the oil in the lower chamber, a pipe connecting the upper and lower chambers, a float operated valve for controlling said pipe, a float operating in the lower chamber and including a float shaft connected to said float valve, an outlet pipe connected to the upper chamber, a gravity operated valve for controlling the outlet pipe, a second shaft connected to the gravity operated valve, arms secured to said shafts and one of said arms having a slot, a connecting rod connected to the other arm and extending through the slot, an arcuately curved dog pivoted on said connecting rod and operating in the slot and spring influenced, and a stop for limiting the pivotal movement of the slotted arm, a pressure transfer pipe connecting the upper and lower chambers and including a pressure relief valve for admitting fluid under pressure through said pressure transfer pipe to the upper chamber from the lower chamber when the pressure in the lower chamber exceeds the pressure in the upper chamber, and a relief valve connected to the upper chamber for sustaining the pressure in the upper chamber below the pressure in the lower chamber.

8. A claim according to claim 7, in which the means for admitting a chemical to the upper chamber comprises a pump connected to a port in said chamber.

GLENN E. MAWHIRTER.
